UNITED STATES PATENT OFFICE.

CHARLES W. HOWELL AND ARTHUR E. HOWELL, OF NEWARK, NEW JERSEY, ASSIGNEES TO UNDERWOOD TYPEWRITER COMPANY, OF NEW YORK, N. Y., A CORPORATION OF DELAWARE.

SHEET-FEEDING DEVICE.

1,196,361.

Specification of Letters Patent. Patented Aug. 29, 1916.

Application filed February 29, 1912. Serial No. 680,689.

To all whom it may concern:

Be it known that we, CHARLES W. HOWELL and ARTHUR E. HOWELL, both citizens of the United States, and both residing in Newark, county of Essex, and State of New Jersey, have invented certain new and useful Improvements in Sheet-Feeding Devices of which the following is a specification.

This invention relates to sheet-feeding devices especially those intended for use in connection with revolving mimeographs or duplicators, and is illustrated in connection with the well-known Underwood revolving duplicator.

The principal object of the invention is to provide, at low cost, a simple, durable and reliable sheet-feeding mechanism.

A revolving separator withdraws the top sheet from a clip, and an oppositely revolving segment then engages the sheet to advance it to the stenciling machine. These revolving members may be covered with soft rubber, and connected by a single train of gearing to the stencil cylinder of the duplicating machine. Preferably, the table which supports the pile of sheets is pressed upwardly by means of springs, so that it rises as the pile diminishes. The revolving separator and feeder are preferably mounted upon a hinged frame, which may be swung up to clear the sheet pile, for convenience in manipulating the sheets. The pressure roll of the stencil machine is usually releasable, and there is connected to the roll-releasing mechanism a device whereby said hinged frame is raised, so that the feeders clear the sheet pile.

Other features and advantages will hereinafter appear.

In the accompanying drawings, Figure 1 is a perspective view of an Underwood revolving duplicator provided with the present improvements, and showing the sheet separator in contact with the pile of sheets.

Fig. 2 is a partial sectional side elevation, showing a sheet advanced by the sheet feeders and passing between the rolls of the stenciling machine. Fig. 2a shows the feeder released from the pile of sheets. Fig. 3 is

a sectional side elevation of the combined feeding and stenciling mechanism. Fig. 4 is a view of the machine from the opposite side of Fig. 2. Fig. 5 is a perspective view to illustrate the means whereby the pressure roll of the stenciling machine is re-

leased, and the hinged feeder frame is raised from the pile. Fig. 6 is a rear elevation of one side of the feeder mechanism.

The usual stencil cylinder 1 is rotated by a handle 2 or otherwise, and has a gear 3 meshing with a driving gear 4 of the sheet-feeding mechanism. Said driving gear 4 meshes with a gear 5, which is fixed upon a horizontal cross shaft 6; and upon this shaft are two paper-feeding segments 7, one at 65 each side of the machine, to engage the sheets near their side edges. This feeder shaft revolves constantly in a single direction. The feeders 7 are in the form of segments having soft rubber facings 8 to contact with the paper-sheets. The segments move alternately into and out of engagement with the pile during their normal revolution, and are of sufficient dimensions to advance a sheet from the pile to the bite of 75 the stencil cylinder 1 and the usual soft rubber roll 9.

The pile of sheets is carried upon a table 10, which is pressed upwardly. At the forward edge of the pile the sheets are caught 80 under a pair of fixed clips 12, which have sharpened edges for convenience in separating the sheets, and for facilitating the advance thereover of the separated sheet. To separate the top sheet from the rest of the 85 pile, and withdraw it from the clips 12, a pair of separators 13, 14, is utilized. These separators 13, 14, may be in the form of arms having soft rubber contacts or friction devices 15, and are mounted, respectively, upon shafts 17, 16 at the sides of the machine; the segments 7 being preferably mounted between these separators, as shown. The separators, like the feeders, move alternately into and out of contact with the pile 90 during their normal revolution.

The separator arms 13, 14 revolve constantly in the opposite direction from the segments 7; being connected by pinions 18 to pinions 19, the latter fixed upon the 100 feeder shaft 6; the separators making one revolution for each revolution of said shaft. During the interval when the segments are out of engagement with the pile, the separators engage the top sheet and draw back 105 its leading edge, buckling said sheet, as at Fig. 3, back against a rear gage 20. As will also be seen at Fig. 3, said sheet is immediately gripped by the soft rubber periphery 8 of the segments, and advanced thereby along 110

a shelf 21 to the bite of the stenciling rolls 1, 9. The sheet is never out of control, since the feeders grip the same at the instant or just before it is released by the separators 13, 14. A weight 22 rests upon the rear edge of the pile, and has a pivotal connection at 23 with a vertical slot in the gage 20, to permit it to rise and fall.

The machine runs smoothly and may be operated with rapidity, since the requisite backward and forward movements of the sheet are effected by devices which revolve continuously and smoothly in unchanging directions; while, owing to the simplicity of the mechanism, the device may be cheaply manufactured, and is durable and not liable to get out of order.

The table 10, on which the pile rests, is supported by draw springs 24, connected to arms 25 upon levers or bell cranks 26, which are loosely mounted upon a horizontal rod 27, mounted in fixed ears 27^a beneath the table at about the middle thereof. Two levers 26 extend forwardly and two rearwardly at each of the sides of the table, and each lever carries at its outer end a roll 28, to press up against the under side of the table; whereby the sheets are pressed lightly up against the clips 12.

The table 10 is guided independently at each of its sides by means of two pairs of levers 29, 30, the levers in each pair pivoted together midway of their ends, at 32; a single transverse floating shaft 31 preferably serving as a pivot for both pairs of levers. Each lever is pivoted at one end at 33 to the framework of the machine, and the other end has a pivot 34 working in a slot 35; these slots formed in brackets 36 fixed to the under side of the table at its forward and rear ends. Each lever 30 in coöperating with its adjacent lever 29, forms a parallel motion device for its side of the table, *i. e.*, if one end of the table is depressed, the opposite end is likewise depressed, and vice versa. Each of the springs 24 has a turnbuckle 37, and by reason of the described construction of springs and guides, the table may be universally adjusted since the upward pressure on either side thereof may be increased by turning the turnbuckles 37 on that side, independently of the pressure at the other side of the table, since one pair of levers 29, 30 is not operatively connected to the other pair, but permits elevation or depression of one side of the table independently of the other side thereof; and there may be strengthening or weakening of the springs on either side without increasing or diminishing the pressure at the other side of the table. Moreover either a rear spring or a forward spring may be independently adjusted, if required.

To place a pile of sheets on the table, the operator presses down thereon midway be-

tween its opposite sides, so that the whole table descends; and a hook 38 upon the rear end of the table may pass down through a hole 39 in latch plate 40, and be caught by a latch 41 pivoted on said plate. The separators and feeders may also be swung up on a pair of arms 42, which are pivoted concentrically to the gear 4, so that the gear 5 always remains in mesh therewith; and a gravity latch 43, Fig. 2, may hold the arms and feeders in elevated positions. Said latch normally hangs in a hole in the shelf or plate 21, as at Fig. 2, but is adapted to rest upon said plate when the feeder-frame is swung up. The arms 42 are rigidly connected by a tie rod 44, upon which the hollow gear-shaft 6 rotates; the arms and rod forming a frame. The pile is now laid upon the table with its forward edge beneath the clips 12, and the side gages 45 are adjusted, as well as the rear gage 20. The latch 41 is then released, and the springs 24 lift the table and pile up against the clips 12.

The gears 18 are provided each with a guard wheel 46 close thereto and of larger diameter, so that the sheets cannot at any time contact with said gears. One of the arms 42 of the swinging feeder frame is provided with an extension 47, to rest upon a stop 48 provided upon the framework of the machine, when the feeder-frame is dropped to working position. The parts are so timed that upon revolving the handle 2 of the stenciling machine, the separators 13, 14 will withdraw the leading edge of the top sheet of the pile, buckling said sheet, as at Fig. 3, and will relinquish the sheet when the feeders 7 engage it, whereupon the sheet is fed over the clips 12 and on to the stenciling machine; this operation being repeated for every revolution of the stenciling machine crank 2. The shaft 17 on which turns one of the gears 18, is connected by a yoke 49^a to arm 47, the yoke giving clearance for the gear 5.

The soft rubber pressure roll 9 of the stenciling machine is releasable, to permit the cylinder to be rotated idly for convenience in inking, etc. For this purpose, the pressure roll 9 is mounted upon arms 50, which are connected by a cross-bar 51, the latter normally held up by a cam 52, which is fixed upon a rock shaft 53. Also fixed to said rock shaft is an arm 54, normally held down by a latch 55. When said latch is released, the arm 54 swings up to the dotted-line position, Fig. 5, the cam 52 also turning to the dotted-line position, and bar 51 dropping, together with the roll 9. Upon the rock shaft 53 is an arm 56, which is connected by a link 57 to a lever 58, pivoted at 59 upon the framework and having at its opposite end a pin 60 to take under one of the arms 42, to lift the feeders from the sheet pile when the stencil roll 9 is released, so that the stencil-

ing cylinder 1 can be revolved without feeding any sheets. Each of the feeding segments 7 is provided with a peripheral groove 61, Fig. 6, in which the endless soft rubber band 8 is seated; said band being stretched through this groove and over the edges and hub of the segment, Figs. 1 and 3. The band is endwise adjustable, so that if it becomes worn, a new surface can be brought into use. Moreover, the band may be taken off and turned inside out and replaced with the fresh surface exposed. We have found that if an acid-cured rubber band is used, the fed sheets will not be soiled by the band.

As soon as the sheet advancing from the pile is presented to the bite of the stencil rolls 1, 9, a separation is automatically effected between the feeding segments 7 and said advancing sheet; or at least the pressure between the feeders and the sheet is relieved. In the present instance, this relief is effected by means of a cam 61^a fixed upon the revolving shaft 16 of the separator 14, to engage a projection 61^b fixed on the framework, whereby the entire feeder frame 42, 44, etc., is raised or supported just as the stencil rolls catch the sheet. The cam has a dead surface 61^c concentric with shaft 16, and of sufficient length to hold up the feeder frame until the longest sheet gets past the feeding-segment 7. This movement of the feeders is, of course, independent of their movement out of contact with the pile, which takes place during the normal revolution of the feeders due to their segmental shape.

The band 15 on the separator is stretched over the hub of the arm 14, and the latter has a serrated point or tip 62, Fig. 6, which catches the rubber band, and prevents the latter from creeping longitudinally. This band may also be slipped around, to present new surfaces for wear; and may also be turned inside out and placed back on the arm. The rubber band 15 is drawn tightly upon the serrations 62, so as to present to the pile of sheets a series of spaced, rubber-covered, feeding fingers or protuberances or relatively hard spots, as indicated at 62^a, Fig. 6; this contrivance being of material benefit in withdrawing the top sheet from the clips, as the serrations or series of points render the separator capable of handling a great variety of sheets, while the liability of withdrawing more than one sheet at a time from the clip is minimized or eliminated. It will be noted that as illustrated herein, said teeth form a row transverse to the direction of movement of the separator. Each separator 13, 14 is preferably slightly over-size; so that when these separators strike the pile, they depress the paper table 10 sufficiently to relieve the pressure between the pile and the clips 12, so that the top sheet is easily withdrawn therefrom. The springs 24 may be so adjusted that the weight of the

feeders and the feeder-frame 42, 44, will overbalance said springs 24.

The paper table 10 is mounted upon a section of the framework which is detachable from the main framework of the stenciling machine; said detachable portion comprising side plates 63, a rear cross bar 64, and a front cross bar 65, Fig. 3. At the forward end of each side plate 63 is a hook 66, to catch under a pin 67 fixed in an ear 68 of the main frame. Each side plate 63 also has a locking notch 69 to engage a pin 70 which also projects from the main frame. The feeder frame 42 may be swung up, and then the detachable portion or table frame may be swung to release it from the pins 70 and also to become unhooked from the pins 67, whereupon the detachable portion may be withdrawn. Each side plate 63 is also provided with a rest or support 71, to rest in a jog 72 in the base of the stencil machine frame; said supports being pivoted to the side plates 63 at 73.

Variations may be resorted to within the scope of our invention, and portions of the improvements may be used without others.

Having thus described our invention, we claim:

1. In a sheet-feeding machine, the combination of a feeder constantly revolving in one direction and moving, during its normal revolution, alternately into and out of contact with the pile of sheets; a separator constantly revoluble in the opposite direction and effective, when the feeder is out of contact with the pile, to withdraw the top sheet and hold it until gripped by said feeder; and means for periodically raising said feeder bodily above the pile, independently of its normal revolving movement out of contact with said pile, to relieve the pressure between said feeder and the sheet gripped thereby.

2. In a sheet-feeding machine, the combination of a feeder constantly revolving in one direction and moving, during its normal revolution, alternately into and out of contact with the pile of sheets; a separator constantly revoluble in the opposite direction and effective, when the feeder is out of contact with the pile, to withdraw the top sheet and hold it until gripped by said feeder; a movable frame whereon said feeder is mounted; and means for periodically raising said frame bodily, to lift the feeder above the pile independently of its normal revolving movement out of contact with said pile, to relieve the pressure between said feeder and the sheet gripped thereby.

3. In a sheet-feeding machine, the combination of a feeder constantly revolving in one direction and moving, during its normal revolution, alternately into and out of contact with the pile of sheets; a separator constantly revoluble in the opposite direction

- and effective, when the feeder is out of contact with the pile, to withdraw the top sheet and hold it until gripped by said feeder; and means for simultaneously raising said feeder and said separator bodily above the pile at definite periods, independently of their normal revolving movement out of contact with said pile, to relieve the pressure between said feeder and the sheet gripped thereby. 70
4. In a sheet-feeding machine, the combination of a feeder constantly revolving in one direction and moving, during its normal revolution, alternately into and out of contact with the pile of sheets; a separator constantly revoluble in the opposite direction and effective, when the feeder is out of contact with the pile, to withdraw the top sheet and hold it until gripped by said feeder; a movable frame whereon said feeder is mounted; and a cam device associated with said frame for raising it bodily at definite periods, to lift the feeder above the pile independently of its normal revolving movement out of contact with said pile, to relieve the pressure between said feeder and the sheet gripped thereby. 75
5. In a sheet-feeding machine, the combination of a feeder segment revolving in one direction and moving, during its normal revolution, alternately into and out of contact with the pile of sheets; a separator, in the form of a contact device, revolving in the opposite direction and likewise moving, during its normal revolution, alternately into and out of contact with the pile; and means for periodically raising said feeder bodily above the pile, independently of its normal revolving movement out of contact with said pile, to relieve the pressure between the said feeder and the sheet gripped thereby. 80
6. In a sheet-feeding machine, the combination of a feeder segment revolving in one direction and moving, during its normal revolution, alternately into and out of contact with the pile of sheets; a separator, in the form of a contact device, revolving in the opposite direction and likewise moving, during its normal revolution, alternately into and out of contact with the pile; a hinged frame whereon said feeder is mounted; and means for periodically raising said frame bodily, to lift said feeder above the pile, independently of its normal revolving movement out of contact with said pile, to relieve the pressure between the feeder and the sheet gripped thereby. 85
7. A rotary paper-feeding member comprising a frame or support having deep teeth at the point where it seizes the sheet; and a strip of elastic, friction material stretched tightly around said frame and passing over said teeth, whereby said strip will be forced outward by the teeth, to prevent the sheet from slipping off the teeth. 90
8. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments and hold a sheet till gripped by said segments, and a hinged frame upon which said segments and separators are mounted to be swung off from the pile. 95
9. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments and hold a sheet till gripped by said segments, a gear upon said shaft, a driving gear meshing with said gear, and a frame upon which said segments and separators are mounted to be swung off from the pile, said frame hinged concentrically with said driving gear. 100
10. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, and means to latch said frame in lifted position. 105
11. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, a rest for said hinged frame when in normal position, means to cause pressure between the pile 110
12. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, a rest for said hinged frame when in normal position, means to cause pressure between the pile 115
13. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, a rest for said hinged frame when in normal position, means to cause pressure between the pile 120
14. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, a rest for said hinged frame when in normal position, means to cause pressure between the pile 125
15. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, a rest for said hinged frame when in normal position, means to cause pressure between the pile 130

and both said separators and feeders, and guard rolls mounted adjacent to said separators and feeders.

12. The combination of a table to support a pile of sheets, a hinged frame, a sheet-feeding mechanism including members mounted on said hinged frame and movable thereon up from the pile, a pair of rolls to which the sheets are fed, means for releasing or separating said rolls, and means connected to said roll-releasing means for lifting said hinged frame.

13. In a sheet-feeder, the combination with a sheet-supporting table, of a pair of parallel-movement linkages, one at each side of the table, said linkages independent of each other, and means for yieldingly supporting the table on said linkages whereby one side of the table may be depressed independently of the other, while the ends of the table must rise or fall together.

14. In a sheet-feeder, the combination with a sheet-supporting table, of a pair of parallel-movement linkages, one at each side of the table, said linkages independent of each other, whereby one side of the table may be depressed independently of the other, while the ends of the table must rise or fall together, and means for applying spring pressure to the corners of the table.

15. A rotary sheet-feeding or separating arm provided at its tip with a row of deep teeth; and a strip of soft rubber stretched tightly around said arm and passing over said teeth, whereby said strip will be forced outward by the teeth, to present to the sheet a row of spaced, rubber-covered, sheet-engaging protuberances or fingers.

16. A rotary paper-feeding arm provided at its tip with a row of deep teeth; and an endless band of yielding friction material stretched tightly around said arm and passing over said teeth, whereby said band will be forced outward by the teeth, to present to the sheet a row of sheet-engaging protuberances or fingers covered with said material, said band being shiftable longitudinally and capable of being turned inside out, to present different portions of its inner and outer surfaces to the paper and to said teeth.

17. A sheet-feeding and stenciling machine comprising a framework, a stencil cylinder, a feeder frame, feeders on said frame connected to said stencil cylinder and movable thereon away from the pile of sheets, an over-size separator to intermittently engage the pile, and a depressible table for supporting said pile.

18. The combination of a sheet-feeding segment movable alternately into and out of contact with the pile of sheets, during its normal revolution, to advance a sheet from the pile; a separator arranged to engage the pile alternately with said segment; a frame

whereon said segment and separator are mounted; rolls to which the sheet is advanced by said segment; and means timed to raise said frame when the sheet enters the bite of said rolls, to relieve the pressure of said segment on said sheet.

19. In a sheet-feeding machine, the combination with a pair of clips for the leading edge of the pile, of a pair of segments, a shaft on which said segments are fixed, means for revolving said shaft, a pair of separators, each in the form of a contact device, gearing from said separators to said shaft to cause the separators to revolve in the opposite direction from said segments to engage the pile alternately with said segments, a hinged frame upon which said segments and separators are mounted to be swung off from the pile, rolls to which the sheets are fed, a cam connected to revolve with said shaft, and means to coöperate with said cam to lift the segments when the advancing sheet reaches the bite of said rolls.

20. The combination with a table and yielding means to sustain the same, of stationary clips over the table, an oversize separator or separators to engage the pile on the table and slightly depress the table while withdrawing the top sheet from the clips and a feeder or feeders to grip the sheet from the separator before the separator releases it.

21. The combination with a table and yielding means to sustain the same, of stationary clips over the table, an oversize revolving separator or separators to engage the pile on the table and slightly depress the table while withdrawing the top sheet from the clips, and means gripping the sheet before the separator releases it to advance the separated sheet.

22. In a sheet-feeder, the combination of a table to support a pile of sheets, yielding supports for the forward and rear ends of the table at each of its sides, and means separate from said supports to cause the table to float on said supports.

23. In a sheet-feeder, the combination of a table to support a pile of sheets, springs for supporting said table at the sides thereof, including two springs for each end of the table, means for adjusting the tension of any spring independently of the others, and means to cause the table to float on said springs.

24. In a sheet-feeder, the combination of a table to support a pile of sheets, springs for supporting said table at the sides thereof, including two springs for each end of the table, means for adjusting the tension of any spring independently of the others, a cross shaft, supporting arms or levers mounted upon said cross shaft and extending forwardly and rearwardly from said

shaft to engage the table, said springs being connected to said arms or levers, and means to cause the table to float on said springs.

25. In a sheet-feeder, the combination of 5 a table to support a pile of sheets, springs for supporting said table at the sides thereof, including two springs for each end of the table, means for adjusting the tension of any spring independently of the others, a 10 cross shaft, supporting arms or levers mounted upon said cross shaft and extending forwardly and rearwardly from said shaft to engage the table, said arms or levers having angle-arms to which the springs 15 are severally attached, and means to cause the table to float on said springs.

26. In a sheet-feeding machine, the combination with a table, of springs for moving said table upwardly, fixed clips overlying the table to hold a sheet on said table which underlies said clips, a device on said table for holding the opposite end of said sheet, said springs arranged to independently hold the ends of the table against the 25 clips and said device independently, and means independent of said springs for holding the two ends of said table at the same height.

27. In a sheet-feeding device, the combination with a frame and carrying-away rolls thereon, of a framework detachable from said frame without disturbing said rolls, a table on said framework, a parallel motion device for said table, a spring for 30 urging said table upwardly, and a clip fixed on said frame and overlying a pile of sheets on said table so that the top of said sheets bears a fixed relation to said carrying-away rolls.

40 28. In a sheet-feeding device, the combination with a frame and a carrying-away roll thereon, of a framework detachably mounted on said frame, a table on said framework, a parallel motion device for said 45 table, a spring urging said table upwardly, a clip on said frame arranged to overlie a pile of sheets on said table so that the top sheet bears a fixed relation to said carrying-away roll, a separator for releasing the top 50 sheet from said clip, and a feeder for advancing a separated sheet to said carrying-away roll.

29. In a sheet-feeding device, the combination with a frame and a carrying-away 55 roll thereon, of a framework detachably mounted thereon, a table on said framework, a spring urging said table upward, a clip on said frame arranged to overlie a pile of sheets on said table, a separator mounted on said frame and held thereby so as to operate in a constant relation to the top sheet on said pile, and a feeder advancing the separated sheets to said carrying-away roll.

30. In a sheet-feeding device, the combination with a frame and a carrying-away 60

roll thereon, of a framework detachably mounted thereon, a table on said framework, a spring urging said table upward, a clip fixed on said frame arranged to overlie a pile of sheets on said table, a separator mounted on said frame and held thereby so as to operate in a constant relation to the top sheet on said pile, a feeder advancing the separated sheets to said carrying-away roll, and means for swinging said separator 70 and feeder clear of the pile of sheets. 75

31. In a sheet-feeding machine, the combination with a frame, and a roll on the frame to which a sheet is fed, of a table, springs independently urging the two ends of 80 said table upwardly, a clip on said table arranged to overlie one end of the top sheet on said table, adjustable plates on said table for confining a pile of sheets thereon, a device for holding the free end of the pile, 85 and a parallel motion device supporting said table.

32. In a sheet-feeding machine, the combination, with a table for supporting a pile of sheets; of a separator for removing a 90 sheet from the pile, provided with protuberances at the point where it engages the sheet, said protuberances being arranged in a row which is transverse to the direction of movement of the sheet; and a covering of 95 yielding friction material stretched tightly over said protuberances and forced outward thereby.

33. In a sheet-feeding machine, the combination, with a table for supporting a pile 100 of sheets; of a separator for removing a sheet from the pile, provided with protuberances at the point where it engages the sheet, said protuberances being arranged in a row which is transverse to the direction of movement of the sheet; a covering of yielding friction material stretched over said protuberances and forced outward thereby; and a device for feeding the sheets removed by said separator. 105

34. In a sheet-feeding machine, the combination with a table adapted to yieldingly support a pile of sheets, of a separator for removing the top sheet from the pile, a face of resilient material on said separator, 110 transversely arranged teeth concealed behind said resilient face, and compressing the resilient material at a series of points on said face, and a resiliently-faced feeding device for removing the sheet loosened by 115 said separator. 120

35. In a sheet-feeding machine, the combination with a yieldingly supported table, of a clip above said table against which a sheet on said table will bear, a separator 125 comprising a resilient face, transversely arranged teeth concealed behind said resilient face and forming a row of comparatively hard spots on said face, a feeder for removing a sheet separated by said separator, 130

- and means for removing away from the table a sheet started by said feeder.
36. In a sheet-feeding machine, the combination with a table, of springs at the ends 5 of said table, a lever on each side of said table extending from one end thereof to a fixed point at the opposite end of said table, a corresponding lever at the opposite end of the table, a floating-shaft common to all 10 said levers to which they are pivoted so that said levers form a parallel motion device for each side of said table, and means connected to said springs for pressing said table upward at each side thereof.
37. In a sheet-feeding machine, the combination with a table, of springs for independently pressing the two ends of said table upwardly, means for holding the table parallel to itself lengthwise as it is moved 20 by said springs, and a clip against which a sheet on the table will bear.
38. In a sheet-feeding machine, the combination with a table, of a tension-spring for supporting one end of said table, an 25 elbow lever comprising a long arm supporting said table and extending at a slight angle thereto, and a parallel motion device for guiding the table as it is moved by said spring.
39. In a sheet-feeding machine, the combination with a table and a parallel motion device therefor preventing an unequal elevation of the two ends of the table, of 35 springs for separately supporting the ends of said table, and separately adjustable to independently vary the upward pressure on the two ends of the table.
40. A sheet separator comprising a series of serrations at the point of contact with the 40 sheets, and a soft rubber friction member tightly drawn over said serrations and comprising a series of comparatively hard spots formed by said serrations.
41. In a sheet-feeding machine, the combination of a swinging frame mounted on 45 the machine frame, a rotary feeder and a rotary separator both mounted on said swinging frame, means for continuously rotating said feeder and separator in opposite directions, and a stop to hold said frame in 50 position for the feeder and separator to intermittently engage a pile of sheets supported below the feeder and separator.
42. In a sheet-feeding machine, the combination, with a clip for the leading edge of 55 the pile of sheets; of a revolving feeder to alternately move into and out of contact with the pile; a separator effective when said feeder is out of contact with the pile, for withdrawing the top sheet from the clip 60 and holding it until gripped by the feeder; and a hinged frame upon which said feeder and separator are mounted to be swung off from the pile.
43. In a sheet-feeding machine, the combination, with a clip for the leading edge of the pile of sheets; of a revolving feeder to alternately move into and out of contact with the pile; a separator effective when said feeder is out of contact with the pile, 70 for withdrawing the top sheet from the clip and holding it until gripped by the feeder; a table; means to lift the table as the pile diminishes; and a hinged frame upon which said feeder and separator are mounted to be 75 swung off from the pile.
44. In a sheet-feeding machine, the combination, with a clip for the leading edge of the pile of sheets; of a revolving feeder to alternately move into and out of contact 80 with the pile; a separator effective when said feeder is out of contact with the pile, for withdrawing the top sheet from the clip and holding it until gripped by the feeder; a shaft to which said feeder is fixed; means 85 for revolving said shaft; gearing from said separator to said shaft, to cause the separator to revolve in the opposite direction from the feeder and hold a sheet until gripped by said feeder; and a hinged frame upon 90 which said feeder and said separator are mounted to be swung off from the pile.
45. In a sheet-feeding machine, the combination, with a clip for the leading edge of the pile of sheets, of a revolving feeder 95 to alternately move into and out of contact with the pile; a separator effective when said feeder is out of contact with the pile, for withdrawing the top sheet from the clip and holding it until gripped by the feeder; a shaft to which said feeder is fixed; means 100 for revolving said shaft; gearing from said separator to said shaft, to cause the separator to revolve in the opposite direction from the feeder and hold a sheet until gripped by 105 said feeder; a gear upon said shaft; a driving gear meshing with the first-named gear; and a frame upon which said feeder and said separator are mounted to be swung off from the pile, said frame being hinged concentrically with said driving gear.
46. In a sheet-feeding machine, the combination with a clip for the leading edge of the pile of sheets; of a revolving feeder to alternately move into and out of contact 110 with the pile; a separator effective when said feeder is out of contact with the pile, for withdrawing the top sheet from the clip and holding it until gripped by the feeder; a shaft to which said feeder is fixed; means for revolving said shaft; gearing from said separator to said shaft, to cause the separator to revolve in the opposite direction from the feeder and hold a 115 sheet until gripped by said feeder; a hinged frame upon which said feeder and separator are mounted to be swung off from the pile; and means to support said frame in lifted position.
47. In a sheet-feeding machine, the com- 120
- 125
- 130

bination, with a pair of clips for the leading edge of a pile of sheets; of a pair of feeder segments; a shaft whereon said segments are mounted; means for rotating said shaft, to cause said segments to move alternately into and out of contact with the pile during their normal revolution; a pair of separators, each in the form of a contact device, for withdrawing and holding the sheet until gripped by said segments; gearing from said shaft to said separators, to cause the latter to revolve in the opposite direction from said segments and to engage the pile alternately therewith; a movable frame whereon said shaft and said separators are mounted; and means for periodically raising said frame bodily, to lift said segments above the pile, independently of their normal revolving movement out of contact with said pile, to relieve the pressure between said segments and the sheet gripped thereby.

48. In a sheet-feeding machine, the combination, with a pair of clips for the leading edge of a pile of sheets; of a pair of feeder segments; a shaft whereon said segments are mounted; means for rotating said shaft, to cause said segments to move alternately into and out of contact with the pile during their normal revolution; a pair of separators, each in the form of a contact device, for withdrawing and holding the sheet until gripped by said segments; gearing from said shaft to said separators, to cause the latter to revolve in the opposite direction from said segments and to engage the pile alternately therewith; and a pivoted frame whereon said shaft and said segments are mounted, movable upwardly to carry said segments and separators clear of said pile.

49. In a stenciling machine, the combination, with a stencil cylinder, and a pressure-roll coating with said cylinder and arranged beneath the same; of a revolute element for feeding sheets to said cylinder; a movable frame whereon said element is mounted; and connections between said pressure-roll and said frame for simultaneously lowering the former and raising the latter, whereby said pressure-roll and said feeding element are moved into inoperative position.

50. In a stenciling machine, the combination, with a stencil cylinder, and a pressure-roll therefor; of a sheet-feeder; a movable frame whereon said feeder is mounted; a

cam coacting with said roll, for normally holding the same in operative position; a rock-shaft to which said cam is secured; a controlling member for said shaft; and connections between said shaft and said frame for causing the latter to move bodily in unison with the former.

51. In a stenciling machine, the combination, with a stencil cylinder, and a pressure-roll therefor; of a sheet-feeder; a cam coacting with said roll, for normally holding the same in operative position; a rock-shaft to which said cam is secured; and connections between said shaft and said feeder for automatically moving the latter bodily into inoperative position when said cam is released from such coaction.

52. In a stenciling machine, the combination, with a stencil cylinder, and a pressure-roll therefor; of a sheet-feeder; a cam coacting with said roll, for normally holding the same in operative position; a rock-shaft to which said cam is secured; an arm secured to said shaft; a latch arranged to engage said arm, to retain said cam in effective position with relation to said roll; and connections between said shaft and said feeder for automatically moving the latter bodily into inoperative position when said latch is released from said arm.

53. In a stenciling machine, the combination, with a stencil cylinder, and a pressure-roll therefor; of a sheet-feeder; a movable frame whereon said feeder is mounted; a device coacting with said roll, for normally holding the same in operative position; and connections between said device and said frame for automatically moving the latter bodily in one direction when the former is released from such coaction, to shift said feeder into inoperative position.

54. A movable, paper-feeding member comprising a frame or support having deep teeth at the point where it seizes the sheet, said teeth being spaced apart from one another; and a strip of yielding, friction material stretched tightly over said teeth, whereby said strip will be forced outward by the teeth, to present to the sheet a series of spaced and covered, sheet-engaging protuberances or fingers.
